Primary Examiner — Darlington Ly(74) *Attorney, Agent, or Firm* — Lucas & Mercanti, LLP(57) **CLAIM**

The ornamental design for a chain ring for bicycle or motorcycle, as shown and described.

DESCRIPTION

FIG. 1 is a left side perspective view of a portion of a first embodiment of a chain ring for bicycle or motorcycle;

FIG. 2 is a right side perspective view thereof;

FIG. 3 is a left side elevation view thereof;

FIG. 4 is a right side elevation view thereof;

FIG. 5 is a top plan view thereof, wherein the bottom plan view is a mirror image thereof;

FIG. 6 is an enlarged top plan view encompassed by the broken line circle in FIG. 5 thereof;

FIG. 7 is a close up right side view of a tooth of the chain ring, wherein the left side view is a mirror image thereof;

FIG. 8 is a close up right side view of another tooth of the chain ring, wherein the left side view is a mirror image thereof;

FIG. 9 is a rear elevation view of a portion of the chain ring thereof; and,

FIG. 10 is a front elevation view thereof.

The broken lines in the drawings illustrate portions of the chain ring for bicycle or motorcycle that form no part of the claimed design.
